UNITED STATES PATENT OFFICE.

CHARLES HARRISON GIBBONS AND JOSEPH P. CLEAL, OF TORONTO, ONTARIO, CANADA.

PHONOGRAPH-STARTING DEVICE.

1,338,365.

Specification of Letters Patent. Patented Apr. 27, 1920.

Application filed May 16, 1919. Serial No. 297,611.

To all whom it may concern:

Be it known that we, CHARLES HARRISON GIBBONS and JOSEPH PACY CLEAL, both subjects of the King of Great Britain, and 5 residents of the city of Toronto, county of York, Province of Ontario, in the Dominion of Canada, have invented certain new and useful Improvements in Phonograph-Starting Devices, described in the following 10 specification and illustrated in the accompanying drawings, that form part of the same.

The principal objects of this invention are, to insure the proper placing of the reproducer of a phonograph upon the record so 15 as to obviate the spoiling of the record through the slurring of the point across it and to insure the piece being started at the beginning and further to prevent the injury of the delicate reproducer points.

The principal feature of the invention 20 consists in the novel construction and arrangement of parts whereby the reproducer point is conveyed to the proper position and 25 automatically deposited upon the record by a horizontally arranged rotatable tapered member.

In the drawings, Figure 1 is a side elevational view of the device showing the 30 phonograph reproducer in position thereon and the record and supporting disk wheel in part section.

Fig. 2 is a plan view of the device.

Fig. 3 is a front elevational view.

Fig. 4 is a front elevational view showing 35 the reproducer point resting upon the locating member, the record and supporting disk being shown in section.

Fig. 5 is a side elevational view showing 40 a modified form of the device.

Fig. 6 is a front elevational view of the device shown in Fig. 5.

The undesirable features incident to 45 starting phonograph records are well known and it is extremely desirable to provide a device which will insure the proper placing of the reproducer point upon the first groove of the record and which will relieve the operator from the necessity of the 50 excessive care at present necessary.

The device herein shown consists of a frame 1 mounted on a base 2 which is secured to the phonograph case, the frame 1

being pivotally connected at one end by a bolt or rivet connection 3. One end of the 55 frame is formed with a pair of uprights 4 and 5 in the upper ends of which is slidably and rotatably supported a spindle 6.

To the inner end of the spindle 6 is secured a spirally grooved tapered member 7 60 which forms the operative member for placing the reproducer point. The inner end is adapted to be adjusted to register with the outer groove of the phonograph record so that upon the rotation of the spindle the 65 reproducer point will be carried inwardly and gradually lowered so that when the reproducer reaches the inward end it slips off into the first groove and the playing of the 70 piece commences.

The spindle 6 is rotated by means of a bevel gear 8 journaled in the upright 4 of the frame being slidably keyed to the spindle.

An indicator guide in the form of a flat 75 strip of metal 9 is slidably arranged in slots in the upper ends of the uprights 4 and 5 and the inward end is bent downwardly and loosely encircles the spindle and its lower extremity 10 is bent inwardly and projects 80 opposite to the inner end of the member 7. The inner edge of the guide extends close to the phonograph record 11 and enables the person setting the device to gage the exact 85 location of the first groove.

The outward end 12 of the spindle is formed with a succession of parallel grooves forming a rack and a transversely arranged spindle 13 is provided with a toothed wheel 14 engaging said rack to enable the spindle 90 being quickly adjusted to suit different diameters of records.

A horizontal extension 15 of the upright 5 is formed with a pair of lugs 16 and 17 supporting the spindle 13, said spindle being provided with a thumb nut 18.

A lug 19 extends inwardly from the top of the horizontal extension 15 and forms the upper journal for an upright spindle 20 which carries a rubber surfaced driving 100 wheel 21 which is adapted to engage the flanged periphery of the disk wheel 22 of the phonograph.

The wheel 21 is held in contact with the disk wheel by means of a coil tension spring 105 23 secured at one end to the pivotal frame

1 and at the other end to a lug 24 on the base.

A shaft 25 is journaled at one end in a downwardly extending lug 26 forming part of the lug 19 and at the other end in a lug 27 forming part of the upright 4. This shaft is provided with a bevel gear 28 meshing with the bevel gear 8 and at the other end has a bevel gear 29 meshing with the gear 30 on the upright spindle 20. The rotation of the wheel 21 is thus transmitted to the spindle 6 and rotates the tapered member 7.

In the use of this device, when a record is placed upon the disk wheel 22 the thumb nut 18 is rotated to slide the spindle 6 in its bearings inwardly or outwardly until the extremity 10 of the guide 9 coincides with the outer groove of the record.

20 On the starting of the disk wheel the wheel 21 is rotated and it is then merely necessary to drop the reproducer needle into contact with the tapered member 7 and the rotation of the tapered grooved surface carries the reproducer inwardly until as it reaches its point it drops into the groove. This device entirely eliminates the necessity of the operator finding the groove with the reproducer point when the machine has been 25 started and as the tapered member 7 is of considerable length it is quite easily located.

The tapered member is so arranged that it carries the reproducer into position lowering it gradually until when at the point 30 it merely slips into the groove. The reproducer point is thus protected from injury through careless handling and dropping into place upon the record and the record is also protected.

35 A device such as described is extremely simple, can be applied to any phonograph without interfering with any other part of the machine and does not damage it in any way.

40 In the form of the device shown in Figs. 5 and 6, a U-shaped frame 31 is secured to a base bracket 32 and carries at its upper end the spindle 33 which is identical in structure with the spindle 6 and slides in a bevel gear 34 corresponding with the gear 8. A vertical spindle 35 is journaled in the bracket 32 and carries at its upper end a bevel gear 36 which meshes with the gear 34. This spindle is driven by a belt 37 operated from the driving mechanism and extends around a pulley 38 secured to the lower end of the spindle.

45 A gear wheel 39 is carried on a short spindle supported in bearings from a lug 40 on the frame 31 and meshes with the rack end of the spindle 33.

The needle may be guided directly by the spirally grooved member on the inner end of the spindle 33 but a bracket 41 is here 50 shown secured to the reproducer. This

bracket is of a jaw shape having a wire 42 stretched between the ends of the jaw and this wire is adapted to rest upon the grooved placing member and guides the reproducer into place.

What we claim as our invention is:

1. In a phonograph starting device, the combination with the reproducer, of a member extending over the record carrying member in a fixed position adapted to support the reproducer and to carry it inwardly and deposit it upon the record. 70

2. In a phonograph starting device, the combination with the reproducer, of a rotatable member supported in a fixed position and extending over the record carrying member adapted to support the reproducer and to carry it inwardly and deposit it upon the record. 75

3. In a phonograph starting device, the combination with the reproducer, of a grooved tapered member adapted to be rotated to carry the reproducer inwardly and deposit it upon the record. 80

4. In a phonograph starting device, the combination with the reproducer, of a frame mounted upon the phonograph adjacent to the phonograph disk wheel, a spindle horizontally journaled in said frame, a spirally grooved member secured to the inner end of said spindle and extending over the phonograph record, means for rotating said spindle, and means for adjusting said spindle in relation to the record. 90

5. A phonograph starting device, comprising, a frame pivotally secured at one end adjacent to the phonograph disk wheel, a vertical spindle journaled in said frame having a wheel engaging the periphery of the disk wheel, a spring connected to the pivotal frame and holding said wheel in operative contact with the disk wheel, a spindle horizontally journaled in said frame and operatively connected with said vertical spindle, and a spirally grooved member secured to the inner end of the spindle adapted to deposit the reproducer upon the record. 100

6. A phonograph starting device, comprising, a frame pivotally secured at one end adjacent to the phonograph disk wheel, 115 a vertical spindle journaled in said frame having a wheel engaging the periphery of the disk wheel, a spindle horizontally and slidably journaled in said frame and operatively connected with said vertical spindle, a spirally grooved member secured to the inner end of said spindle and extending over the phonograph record, and means for adjusting said horizontal spindle longitudinally of its bearings. 120

7. A phonograph starting device, comprising, a frame pivotally secured at one end adjacent to the phonograph disk wheel, a vertical spindle journaled in said frame having a wheel engaging the periphery of 130

the disk wheel, a spindle horizontally and slidably journaled in said frame and operatively connected with said vertical spindle and having rack teeth on the outer end, a 5 horizontally journaled spindle arranged transversely of the sliding spindle and having a toothed wheel thereon engaging the rack portion of said spindle, a spirally grooved member secured to the inner end of said spindle, and an indicator point carried by said spindle and extending close to the record.

CHARLES HARRISON GIBBONS.
